Inventor:
Oliver H. Walton,
by
Charles S. Gooding, Atty.

UNITED STATES PATENT OFFICE

OLIVER H. WALTON, OF NEEDHAM HEIGHTS, MASSACHUSETTS

ELASTIC KNITTED FABRIC

Application filed December 7, 1931. Serial No. 579,591.

This invention relates to an elastic knitted fabric of the type in which a plurality of elastic strands extend transversely of the fabric, the object of the invention being to lock the elastic strands in the knitted fabric so that they cannot be pulled out.

The invention consists in an elastic knitted fabric of the character hereinafter set forth and particularly pointed out in the claims.

10 Referring to the drawing:

Fig. 1 is an enlarged elevation of a portion of a knitted fabric embodying my invention.

15 Fig. 2 is an enlarged section taken transversely of one of the elastic strands, a portion 15 of one of the loops of knitted fabric being shown extending through the covering of said strand.

Like numerals refer to like parts in the views of the drawing.

20 In the drawing, 5, 6, 7 and 8 are rib knit courses and 9, 9 are elastic strands. The elastic strands consist of a core of rubber 10 which is surrounded by layers of yarn 11 and 12 wound around the core 10 and constituting a cover 14 of the same. Loops 13 of the different courses 5, 6, 7 and 8 project through the elastic strands 9, preferably through the yarn covering thereof, as illustrated in the figures of the drawing. It will 30 be seen that the loops 13 extending through the yarn covering of the elastic strand firmly lock the strand within the knitted fabric so that it cannot be withdrawn therefrom.

The complete machine for knitting the 35 fabric of this invention is disclosed in application by this applicant Serial No. 593,264 filed February 16, 1932.

I claim:

1. An elastic knitted fabric embodying 40 therein a plurality of elastic strands extending transversely of the fabric, and loops of said fabric projecting through said strands, whereby the strands are locked in said fabric.

2. An elastic knitted fabric embodying 45 therein a plurality of elastic strands extending transversely of the fabric, said strands each comprising a core of rubber and a covering of yarn, and loops of said fabric projecting through said covering whereby the 50 strands are locked in said fabric.

3. A knitted fabric embodying therein a plurality of strands extending transversely of the fabric, and loops of said fabric extending through said strands, whereby the strands are locked in said fabric. 55

4. A knitted fabric embodying therein a strand extending transversely of the fabric, and a loop of said fabric extending through said strand, whereby said strand is locked in said fabric. 60

In testimony whereof I have hereunto set my hand.

OLIVER H. WALTON.
